UNITED STATES PATENT OFFICE.

LUDWIG T. STRUCK, OF WASHINGTON, DISTRICT OF COLUMBIA.

TROUSERS-SUPPORTING DEVICE.

1,427,335.

Specification of Letters Patent. Patented Aug. 29, 1922.

Application filed July 20, 1921. Serial No. 486,033.

To all whom it may concern:

Be it known that I, LUDWIG T. STRUCK, a citizen of the United States, residing at Washington, District of Columbia, have invented certain new and useful Improvements in Trousers-Supporting Devices, of which the following is a specification.

This invention relates to trousers and its object is to provide a novel and improved means for supporting the same without the use of suspenders or an outside belt, and so constructed and arranged that when the trousers are worn they will have the appearance of ordinary belt-supported trousers.

The invention also has for its object to provide a trousers-supporting device which supports the trousers in a most effective manner and without discomfort to the wearer.

A further object of the invention is to provide a supporting device which is made up entirely of ordinary tailor's trimmings, and which can therefore be easily and cheaply made up by a tailor.

Other objects and advantages of the invention will be pointed out in the detailed description appearing hereinafter, and in order that the same may be better understood, reference is had to the accompanying drawing.

In the drawing:

Figure 1 is a perspective view of the improved trousers viewed from the front; Fig. 2 is a similar view showing the rear of the trousers; Fig. 3 is a view similar to Fig. 1 showing a front fall turned down; Fig. 4 is a detail view of a buckle, and Fig. 5 is a detail view showing a ventilated crotch.

Referring specifically to the drawing 10 denotes a pair of trousers having its front formed with a fall 11, the outer face of which has a lap 12 to obtain the appearance of trousers which button up in front and have a fly covering the buttons. Ordinarily, 15 the fall is free of the body of the trousers at both ends so that it may be turned down. However, in the present instance, one end of the fall is free, the other end being integral 20ly or otherwise connected to the trousers body. Fig. 3 clearly illustrates this construction, the fall being here shown turned down.

On the inner face of the fall 11 at the top thereof, is located a band 13 carrying

an ordinary tailor's buckle 14 arranged to 55 have one of its end cross bars 15 engage a hook 16 which is attached to that portion of the trousers front which is lapped by the fall. The band is attached at the site of the side seam of the trousers which determines one end of the fall, this being the attached end, and the free end of the fall terminates at the other side seam. The band is sewed on as shown at 17, or otherwise secured, and it passes midway between its 60 ends under a loop 18 on the inner face of the fall at the middle thereof. The free end of the band which carries the buckle is looped as shown at 19 to prevent loss of the buckle.

For the purpose of holding the fall 11 in 70 closed position I provide the free end thereof, at the top, with a pair of vertically spaced hooks 20 which are engageable with corresponding eyes 21 on the waist portion of the trousers at the site of this portion of 75 the fall when the latter is closed. It will be noted that three pairs of eyes are provided which are spaced circumferentially, which enables a pair of trousers of a given size to be adjusted to fit a person whose 80 waist measure is somewhat greater or less. The spacing will preferably be such that a pair of trousers of a certain size can be adjusted to the next larger and smaller sizes.

As shown in Fig. 2, the top edge of the 85 trousers, at the back, is not parallel to the waist line but has a gradual rise from the side seams to the center so that the trousers here reach somewhat higher up than ordinarily, this being for the purpose of obtaining a snug fit at the back with a resultant proper support for the trousers.

The trousers are supported in proper position on the person by engaging the buckle cross bar 15 with the hook 16, the buckle 14 of course being adjusted to obtain the proper degree of tightness of the belt 13. After the band is secured in this manner, the fall 11 is closed and secured by engaging the hooks 20 with the selected pair of eyes 21. The 90 trousers are now securely held in place on the person without discomfort and without 100 in the least interfering with the freedom of movement.

All the parts are made up of ordinary 105 tailor's trimmings, and hence the trousers can be constructed complete, with the supporting means, in a tailoring establishment.

The eyes 21 can be made with button-hole stitches. The trousers will also be provided with pockets in the usual location.

I claim:

- 5 A trousers having a front wall which is free from the trousers body on one side thereof, a band attached at one end to the inside of the trousers body on the other side thereof, the other end of the band being free, a buckle adjustably mounted on

said free end of the band, a hook carried by the trousers body on the first-mentioned side thereof, the buckle having means for detachable engagement thereof with the hook, and a separable connection between the free end of the fall and the first-mentioned side of the trousers body. 15

In testimony whereof I affix my signature.

LUDWIG T. STRUCK.
